UNITED STATES PATENT OFFICE.

WILLIAM EHRLICH, OF CHICAGO, ILLINOIS.

APPLE PARING, CORING, AND SLICING MACHINE.

1,384,013.

Specification of Letters Patent.

Patented July 5, 1921.

Application filed May 29, 1920. Serial No. 385,192.

To all whom it may concern:

Be it known that I, WILLIAM EHRLICH, a citizen of the United States, residing at Chicago, in the county of Cook and State of Illinois, have invented certain new and useful Improvements in Apple Paring, Coring, and Slicing Machines, of which the following is a specification.

My invention relates to mechanism for paring, coring and slicing apples and other similar fruits and has for one of its objects the provision of a simple and efficient device of the character mentioned.

A further object is the provision of a device of the character mentioned adapted to automatically pare, core and slice apples and other similar fruits.

Other objects will appear hereinafter.

An embodiment of my invention is indicated in the accompanying drawings, forming a part of this specification and in which—

Figure 1 is a side elevation of a device embodying my invention;

Fig. 2 is a section taken on line 2—2 of Fig. 1;

Fig. 3 is an enlarged fragmental section taken on line 3—3 of Fig. 2;

Fig. 4 is an enlarged fragmental section taken as on line 4—4 of Fig. 2;

Fig. 5 is a fragmental view looking as from line 5—5 in Fig. 1;

Fig. 6 is a section taken on line 6—6 of Fig. 1; and

Fig. 7 is a view similar to Fig. 6 but showing parts in different positions.

Referring more particularly to the drawings, I have indicated a frame 10 of suitable form to accommodate the parts hereinafter mentioned. This frame is preferably a casting and may be made up of one or more integral parts or castings when so desired.

Journalized in the casting 10 in suitable bearings is a drive shaft 11 carrying a pulley 12 by means of which the shaft 11 is operated. On the shaft 11 is a pinion 13 meshing with a gear 14, the latter being journalized on a stud shaft 15 threaded in the frame 10, as at 16, or, secured to the frame 50 in any desirable manner.

A shaft 17 is also suitably mounted in the frame 10 and carries an intermittent gear 18 which co-operates with a suitable intermittent gear member 19 formed integrally with or secured to gear 14. Any suitable form of intermittent gear may be used. In

the form shown the gear 14 is adapted to turn three revolutions to one revolution of shaft 17.

On one end of shaft 17 I secure a head 60 20 which carries a plurality of apple-holding forks 21. In the present instance I have indicated three forks 21, but it will be understood that a fewer or greater number may be provided, as desired. The number of revolutions of gear 14 with relation to shaft 17 will correspond to the number of forks 21 used.

Each of the forks 21 is mounted on a sleeve 22 journaled in head 20 and has a gear 23 thereon adapted to be brought into mesh with a gear 24 fixed on a shaft 25 and the latter is operated through a pinion 26 on said shaft 25 meshing with a large gear 27 on shaft 11. The shaft 17 is arranged 75 so that the head 20 can rotate to bring one of gears 23 into mesh with gear 24 to operate one of the forks 21 at a time.

A collar 28 is provided on each of the sleeves 22 for holding said sleeves 22 against 80 longitudinal movement.

Slidably mounted in each of sleeves 22 is a pin 29 adapted for removing a core from a fork 21. Each pin 29 is moved in its sleeve to its position indicated at 29' in Fig. 1 by 85 placing an apple on fork 21. When the apple has moved around until it has passed a place where the apple is completely pared and cored its corresponding pin 29 engages a cam 30 on the frame and moves the pin 90 to its position indicated in the fork 21 near the lower side of Fig. 1. This movement of said pin pushes the core out of fork 21, discharging it from the machine.

Also, adjacent each of the forks 21 is a 95 pusher 31 mounted on a pusher rod 32 which is slidably mounted in head 20. After the apple has been pared and cored a pusher 31 pushes the apple from its fork 21 over onto the coring knife 33, which will be described more in detail later. Each pusher 31 is moved to a position indicated at 31' in Fig. 1 by pressing an apple onto its fork 21 and after the apple has been pared and cored the pusher is moved to the position 105 indicated at the lower side of Fig. 1 by an arm 34 pivoted as at 35 on a bracket 36 secured to frame 10. The arm 34 is operated by a cam 37 on gear 14 and timed so as to push the pusher to proper position 110 after the paring and coring has been completed and before the fork 21 carrying the

apple has been moved out of registration with the coring knife 33. A spring 38 serves to hold the arm 34 in the position shown in Fig. 1, except when being operated upon by cam 37. A friction roller 39 may be mounted on the arm 34 when so desired.

In a suitable part of the frame 10 is provided a guide 40, which in the present instance is indicated as two rods. Slidably mounted on this guide 40 is a carrier 41. This carrier 41 has a vertical opening in which is journaled a shaft 42, see Fig. 4. On the lower end of shaft 42 is a bifurcated member 43 which has two teeth 44, as clearly indicated in Fig. 3. These teeth 44 co-operate with recesses 45 in a guide member 46 secured under a suitable portion of the frame, as at 47. At the top of shaft 42 is a member 48 having a slot 49 at one side thereof in which is pivoted a knife carrier 50, being pivoted as at 51. The member 50 has a part 52 extending away from shaft 42 to which a tension spring 53 is connected. This spring holds the member 50 over toward shaft 42 and provides a resilient mounting for the paring knife. The carrier 41 is cut away, as at 54, to permit the member 50 and spring 53 to move freely in their operation.

The carrier 41 is moved along by a segmental gear 55 fixed on a shaft 56 which is journaled in the frame 10. The gear 55 meshes with teeth 57 on the carrier 41. Said gear 55 is operated by a roller 58 mounted on an arm 59 which is fixed on a shaft 60. The roller 58 operates in a slot 58' in the gear 55. The shaft 60 is rotated by a worm wheel 61 meshing with a worm 62 on a shaft 63, the latter being journaled in a suitable part of the frame 10. The shaft 63 is operated by a pinion 64 fixed thereon which meshes with gear 27.

On the lower end of member 50 is a knife holder 65 having a suitable knife 66 mounted thereon in a manner to engage an apple on the forks 21, one at a time. The member 65 is preferably mounted so that it can swing on member 50, but may be connected rigidly. As the member 41 moves along toward the gear 27 it carries the head 43 along. As member 43 moves along member 46 one of the teeth 44 engages a projection 45' between the notches 45 and rotates the shaft 42, together with knife holder 50.

The parts are so timed that this rotation of member 43 takes place at the time the knife 66 is engaging an apple on one of the forks 21. In Fig. 3 the member 43 is indicated in three of its positions and from this it will be clear how the member 43 will turn through 180 degrees in going in each of its directions of reciprocating movement. The slot 50' permits the rod 50 to move on its pivot 51 against the influence of spring 53 so that the knife 66 will be held against apples of

different sizes and against apples having irregular surfaces.

The carrier 41 has an arm 68 to which is secured a rod 69 and the latter has the coring knife 33 formed thereon or otherwise attached thereto. The rod 69 and coring knife 33 have a common axis and an axial alignment with fork 21 in a position where an apple is cored on said fork, as clearly indicated in Figs. 1, 6 and 7.

Journaled at one side of frame 10 in bearings 70 is a shaft 71 which carries a holder 72 and an arm 73. The arm 73 is operated by a connecting link 74 connected with a lever 75 and the latter is pivoted on a frame 76, as at 77. To one end of the lever 75 is mounted a roller 78 which engages a cam 79 carried on shaft 60. A spring 80 engages lever 75 and tends to hold roller 78 against cam 79.

In operation the head 20 is adapted to rotate over toward the observer of Fig. 1 so that when an apple is placed on fork 21, as indicated in Fig. 2 at 21°, it will be passing away from the paring mechanism so as not to catch the operator's hands. The device rotates head 20 until the apple reaches the position indicated at 21° in Fig. 2 when the carrier 41 moves the paring knife 66 against the apple and turns the knife so as to keep it facing the apple until the latter is completely pared. The movement of the knife toward the apple also brings the coring knife 33 into the apple, and immediately after the paring is completed, the coring knife 100 has passed entirely through the apple, as indicated by its position in Fig. 7. Immediately after the coring knife has reached this position the arm 34 engages an arm on a pusher rod 32, thus moving its pusher 105 against the apple and moves such apple off of fork 21 and onto the coring knife at substantially the position of the apple A in Fig. 6. Then as the carrier 41 moves on back toward its full line position in Fig. 1 it carries the apple A behind holder 72 which has been moved out of position by its connection with cam 79, permitting the apple to move to the position in the device shown in Fig. 6. During this time the fork upon which the core yet remains moves from position 21° to 21° in Fig. 2, and during this movement pin 29 engages cam 30 and pushes the core out of fork 21, ready to receive a new apple.

Upon the next apple being brought around to its position for being pared and cored holder 72 is moved down to its position indicated in Fig. 5 by cam 79 and connecting mechanism so that when the carrier 41 brings coring knife 33 up against the second apple, the holder 72 will slide the apple along on the coring knife until slicing knives 81 engage the apple, as clearly indicated in Fig. 7, and cut the apple into slices.

This takes place while the second apple is being pared and cored, and should one or more pieces of the first apple stick to the knives 81, when the second apple is brought 5 up to be sliced during the paring and coring of the third apple, this second apple will push the pieces of the first apple off of knives 81.

While I have indicated four knives 81 it 10 will be apparent that as many or as few of these knives may be provided, as desired. It will also be obvious that the parings and cores are dropped near the same point and the good part of the apple is dropped at a 15 different point so that the good apples can be kept away from the parings and corings, if desired.

I claim:—

1. The combination with an apple paring 20 and coring machine having a rod therein mounted for longitudinal movements, of coring and slicing knives fixed on said rod; a holding member mounted for movement adjacent said rod for holding an apple against 25 the slicing knife; and means for moving the holding member laterally away from the rod.

2. In combination, a frame; an apple-holding fork mounted in said frame; a reciprocating member mounted in the frame; 30 a rod substantially alining with the fork on said member; a coring knife on said rod; a pusher adjacent the fork adapted to push fruit from said fork onto said coring knife; a slicing knife on said rod; and a holder 35 adapted to hold fruit while the slicing knife is carried by the rod against said fruit.

3. In combination, a frame; an apple-holding fork mounted thereon; means for 40 rotating said fork; a guide in the frame; a member slidably mounted on said guide and operatively connected with the means for rotating said fork; an arm on said member; a rod disposed substantially in alinement 45 with the fork on said arm; coring and slicing knives on said rod, the coring knife being adapted for movement along close to the fork; means adjacent the fork for moving an apple onto the rod; and a member mounted 50 on the frame for holding said apple against movements back toward said fork.

4. In combination, a frame; an apple fork journaled in the frame; an elongated member mounted for longitudinal movement in 55 the frame toward and away from said fork; means for pushing an apple from the fork onto said elongated member; a slicing knife on said member; a holder mounted to swing toward and away from said member; and 60 means for operating said holder adapted to

move the latter to permit an apple to pass the holder in one direction and move said holder adjacent said member to hold said apple from movement in the opposite direction.

65

5. In combination, a frame; an apple fork journaled in the frame; a rod mounted in the frame for longitudinal movement toward and away from said fork; a coring knife on the rod extending toward said fork; a slicing 70 blade extending radially from the rod; a pusher adapted to move an apple from the fork onto the coring knife; a holder mounted for movement toward and away from the coring knife and rod; and means for 75 moving the holder away from the rod and coring knife when said rod and coring knife are moved away from said fork and adapted to move the holder adjacent said rod and coring knife when said rod and coring knife 80 are moved toward said fork.

6. In combination, a fruit-holding fork; a coring knife; means for rotating the fork and moving the coring knife toward and away from said fork; a holder mounted on 85 an axis at one side of the coring knife; and means operatively associated with the fruit-holding fork and coring knife and connected with said holder adapted to move the latter away from the coring knife to permit the 90 passage of fruit onto the coring knife and adapted for moving said holder adjacent the coring knife to hold said fruit against movement back toward said fork.

7. In combination, a fruit-holding fork; 95 a coring knife; means for rotating the fork and moving the coring knife toward and away from said fork; a holder mounted on an axis substantially parallel to the axis of the coring knife; a cam operatively associated with the coring knife; and an operative connection between said cam and said holder adapted to swing the latter adjacent to and away from the coring knife.

8. In combination, a fruit-holding fork; 105 a coring knife; means for rotating the fork and moving the coring knife toward and away from said fork; a holder mounted on an axis substantially parallel to the axis of the coring knife; a cam operatively associated with the coring knife; a lever having one end operatively engaging said cam; a spring holding said end of the lever against said cam; and an operative connection between said lever and said holder.

In testimony whereof I have signed my name to this specification on this 25th day of May A. D. 1920.

WILLIAM EHRLICH.
